UNITED STATES PATENT OFFICE.

JAKOB BENARIO, OF FRANKFORT-ON-THE-MAIN, GERMANY.

ADHESIVE PLASTER.

1,100,944.

Specification of Letters Patent. Patented June 23, 1914.

Application filed January 28, 1913. Serial No. 744,673.

To all whom it may concern:

Be it known that I, JAKOB BENARIO, doctor of medicine, physician, a subject of the Emperor of Germany, and residing at 1 Savignystrasse, Frankfort-on-the-Main, Germany, have invented a certain new and useful Improvement in Adhesive Plasters, of which the following is a specification.

The object of the present invention is a plaster in which the adhesive is arranged in strips or in areas of any form which lie in another plane than the places free from adhesive so that air channels result which are of great value and importance for the treatment of wounds.

The object of the invention is shown in the accompanying drawing by way of example.

Figure 1 shows the new plaster in plan view seen from the adhesive side and Figs. 2 and 3 are shown in section with the plaster stuck on, while Figs. 4 and 5 show modifications corresponding to Fig. 1.

In the form according to Figs. 1 to 3 the plaster consists of a material on which strips are arranged lying alternately in different planes, of which those lying in the one plane (b) bear the adhesive, and lie against the surface *a* to which the plaster is applied, while the others (c) serve for the passage of air.

The strips *b* can be obtained by causing the adhesive to be raised up or by arranging in the material raised strips woven or raised in other ways, so that suitable air-channels *d* remain beneath the strips *c*, as is evident in Figs. 2 and 3.

It is not necessary for the strips, which

also may be disposed in a wavy or zig-zag manner, to run continuously, but it is quite sufficient if, instead of this there are formed, say right-angled adhesive places *b* according to Fig. 4, or circular adhesive places according to Fig. 5, which also can as easily be made raised in the fabric as continuous raised strips.

Instead of the right-angled or circular areas, any geometric figures can be used which can be grouped in any way regularly or irregularly.

I claim:

1. An adhesive plaster comprising in combination, a pliable fabric backing, raised portions integral with said backing whereby ventilating channels, allowing exudation or the admission of sanative gases, are formed between said raised portions, and an adhesive substance applied to said raised portions so that the adhesive is positioned on portions of the fabric lying in a different plane from the other portions of the fabric.

2. An adhesive plaster, comprising in combination, a pliable fabric backing having raised fabric portions in the form of ribs or spots woven integral with said fabric, said portions being arranged on the backing so as to form ventilation channels therebetween, and an adhesive medicament applied to said raised fabric portions.

In testimony whereof I affix my signature in presence of two witnesses.

DR. JAKOB BENARIO.
